CAPACITY COUPLED CONSTANT
AMPLIFICATION CIRCUITS

Walter van B. Roberts, Princeton, N. J., assignor
to Radio Corporation of America, a corpora-
tion of Delaware

Application October 31, 1932, Serial No. 640,397

10 Claims. (Cl. 250—20)

My present invention relates to coupling systems, and more particularly to improved capacity coupling systems for tuned radio frequency amplifiers which give substantially constant amplification and selectivity over the entire broadcast range.

It is well known in the prior art that the output of a tube may be capacitatively coupled to the tuned input circuit of a second amplifier stage. In such a coupling system the coupling condenser forms a mutual impedance between the plate circuit of the preceding tube and the succeeding tuned circuit. The amplification in such a coupling system is independent of frequency if the resistance of the tuned circuit is independent of frequency. But, if the resistance is constant so also is the selectivity of the tuned circuit. In any actual tuned circuit this is not the case, and the increase of resistance with frequency makes such a capacity coupled system unsatisfactory.

Now, I have discovered novel methods of, and devised improved means for, combining such a capacity coupling network with means for introducing into the succeeding tuned circuit an amount of negative resistance sufficient to reduce the total effective resistance of the tuned circuit to a value which is sufficiently low for good amplification and selectivity and sufficiently constant to maintain both amplification and selectivity satisfactorily constant.

Hence, it may be stated that it is one of the prime objects of this invention to provide in combination with an amplifier tube, means for capacitively coupling the output circuit of the amplifier to a resonant circuit, and additional means for controlling the total effective resistance of said circuit, said additional means being adapted to introduce into the resonant circuit a negative resistance which varies with frequency in such a way as to maintain the total effective resistance substantially constant, or to make it vary with frequency in any other desired way.

Another important object of the present invention is to provide a condensive coupling network between an amplifier tube and a tuned radio frequency circuit, means being provided for controlling the resistance of the tuned circuit so as to maintain the said resistance independent of frequency.

Another important object of the present invention is to provide a condenser coupling between two cascaded amplifier tubes, the second amplifier having a resonant input circuit, wherein the amplifying power of the one of said tubes and the total effective resistance of said resonant input circuit are uni-controlledly adjusted in opposite senses by a single operating means.

Another object of the invention is to provide an amplifier system wherein a preceding amplifier tube is capacitively coupled to the resonant input circuit of another amplifier tube, means being employed for introducing into the resonant circuit an amount of negative resistance sufficient to reduce the total effective resistance of the resonant circuit to a value which is sufficiently low for good amplification and selectivity and sufficiently constant to maintain both amplification and selectivity satisfactorily constant, one of said amplifying tubes and the means for producing negative resistance in said resonant input circuit being both enclosed within the same glass envelope.

Still another object of the present invention is to provide a novel type of tube structure for use in connection with a capacitively coupled amplifier, the said tube structure comprising electron emitting means, a screen grid, a control grid, and two anodes electrostatically shielded from each other by a suitable structure of the screen grid, or instead of employing two anodes, alternatively employing two control grids electrostatically screened from each other by a suitable construction of the screen grid and a screening means at the potential of the cathode.

And still another object of this invention is to provide a light battery operated portable radio receiver utilizing amplifier circuits comprising capacitively coupled tuned radio frequency amplifier stages, each amplifier stage including a novel tube construction, and each of such tube constructions providing an amplifier tube as well as a means for introducing negative resistance into the resonant input or output circuit of each of such amplifier tube constructions.

Still other objects of the invention are to improve generally the simplicity and efficiency of condenser coupled amplifier circuits, and to particularly provide such an amplifier circuit which is not only durable and reliable in operation, but

readily manufactured and assembled in radio receivers.

The novel features which I believe to be characteristic of my invention are set forth in particularity in the appended claims, the invention itself, however, as to both its organization and method of operation will best be understood by reference to the following description taken in connection with the drawings in which I have indicated diagrammatically several circuit organizations whereby my invention may be carried into effect.

In the drawings,

Fig. 1 shows diagrammatically a condenser coupled amplifier for analysis purposes.

Fig. 2 shows a similar circuit to be analyzed,

Fig. 3 diagrammatically shows a capacitively coupled amplifier circuit embodying the present invention,

Fig. 4 shows a modification of the arrangement shown in Fig. 3,

Fig. 5 shows a novel tube construction adapted for use in connection with the present invention,

Fig. 6 shows diagrammatically another modified form of amplifier circuit embodying the present invention,

Fig. 7 is a modification of the arrangement shown in Fig. 6, and showing a novel modified form of tube construction,

Fig. 8 shows a circuit employing a tube construction similar to that shown in Fig. 7 but slightly modified,

Fig. 9 shows a modification of the arrangement shown in Fig. 8,

Fig. 10 shows diagrammatically a portable radio receiver embodying the present invention,

Fig. 11 shows still another modification of the present invention, and

Fig. 12 shows a modified form of the arrangement shown in Fig. 11.

Referring now to the accompanying drawings wherein like reference characters in the different figures designate corresponding circular elements, reference is first made to Fig. 1 which shows a simple capacity coupling between an amplifier tube 1 and a second amplifier tube 2, the coupling being provided by means of the condenser K. The control grids of tubes 1 and 2 are negatively biased with respect to the cathodes by means of the usual grid biasing networks 3 disposed in the grounded cathode leads of both tubes. Potential for the anode of tube 1 is supplied from a source of anode potential B (not shown) through a radio frequency choke coil 4, a direct current blocking condenser 5 being connected between the anode of tube 1 and the coupling condenser K.

Between the control grid and cathode of the amplifier tube 2 is connected a resonant input circuit comprising the variable tuning condenser C connected in series with the inductance coil L, the resistance of the resonant circuit being represented by a resistor r connected in series between the cathode and the inductance coil L. The series resonant path C, L, is connected in shunt across the condenser K, and the radio frequency voltage for the tube 2 is obtained by connecting the control grid and cathode of the tube across the inductance L, the resistor r also being included in this input path.

Representing the radio frequency input to the tube 1 by the symbol E₁, and designating the input to the tube 2 by E₂, and assuming that the load impedance is so low that the tube may

be considered as a generator of constant current, it can be readily shown that the voltage introduced into the tuned circuit of tube 2 is:

$$E_1 G_m \frac{1}{\omega K}$$

The current at resonance is

$$\frac{E_1 G_m}{\omega K r}$$

and therefore

$$E_2 = \left(\frac{E_1 G_m}{\omega K r} \right) (\omega L)$$

It may therefore be stated that the amplification

$$\frac{E_2}{E_1} = \frac{G_m L}{K r}$$

The amplification is independent of frequency if r is constant, and the selectivity is then also constant because

$$\frac{L}{r}$$

is constant.

As is well known, the voltage for the input of tube 2 may be taken off across the tuning condenser C, and Fig. 2 shows such an arrangement, the voltage E₂ being taken across the variable tuning condenser C in order that the condenser rotor may be grounded. At the high frequency end of the tuning range of the condenser C the voltage across this condenser will be almost exactly the same as across the coil L, but at the low frequency end it will be about four-fifths of the voltage across the coil. Thus, Fig. 3 will give constant amplification only if r increases approximately twenty percent with frequency from the lowest to the highest frequency of the tuning range of condenser C.

In any actual tuned circuit the resistance of the tuned circuit does not remain constant but increases with frequency. This increase of resistance with frequency makes capacity coupled systems of the types shown in Figs. 1 and 2 unsatisfactory. It is a well known fact that in a coil such as the coil L, the value of r is not a constant throughout the tuning range of condenser C. Therefore, the present invention contemplates combining such a capacity coupling network with means for introducing into the tuned input circuit of the tube 2 an amount of negative resistance sufficient to reduce the total effective resistance of the tuned circuit C, L to a value which is sufficiently low for good amplification and selectivity and sufficiently constant to maintain both amplification and selectivity satisfactorily constant. Without using the present invention there results in Figs. 1 and 2 a deviation in selectivity and amplification of about 100%. Negative resistance may be introduced into a resonant circuit in several ways well known in the art.

By employing any of the various means disclosed in the present application, there is obtained a coupling system for tuned radio frequency amplifiers which gives substantially constant amplification and selectivity over the entire broadcast band without employing any of the arrangements disclosed heretofore in the prior art. For example, with the constants employed in the present invention the conductance of the coupling system at resonance is so greatly in excess of that of the plate circuit of the preceding tube that it is not a case of a compromise between maximum amplification and maximum selectivity.

ity as contemplated by well known methods of the prior art. In my present arrangement the amplification is so very far from the maximum possible value, and the selectivity substantially that of the tuned circuit alone.

Fig. 3 shows one method of introducing negative resistance into the tunable input circuit of the amplifier tube 2. While a dynatron could be employed for introducing the negative resistance into the tuned input circuit of tube 2, the arrangement shown in Fig. 3 shows an improved method of using an auxiliary tube A whose sole function is to introduce regeneration into the tuned circuit C, L. Another way of stating the latter function is that tube A serves to keep the total effective resistance of the resonant circuit K, C, L constant. The grid of tube A is connected by a lead 6 to the grid of tube 2, and the anode of tube A is connected to the grounded cathode lead through a series path which includes the coil T₁, the coil T₂ shunted by condenser K₂, and the anode potential source B'.

The output of tube A is coupled to the coil L by a pair of couplings, in this case by mutual inductance, between coils T₁ and T₂ and L. This coupling is well known to the art as "compound coupling", the couplings depending on the tubes and circuits used and being so chosen that the feed-back, or negative resistance, introduced into the tuned circuit K—C—L varies with frequency in such manner that the total effective resistance remains approximately constant. As pointed out heretofore such an operating condition necessarily results in the amplification and selectivity remaining substantially constant throughout the tuning range of the condenser C.

In Fig. 4 there is shown a modification of the arrangement shown in Fig. 3 wherein there is employed a volume control device R, disposed in the grounded cathode lead of tube 2, which acts to uni-controlledly vary the amplification of the amplifier tube 2 and the amount of regeneration of the regenerative tube A. Only so much of Fig. 3 is shown in Fig. 4 which is essential to an understanding of the modification, it being pointed out that the cathode of the auxiliary tube A is connected directly to the cathode of the amplifier 2. Hence, the bias on both tubes is always the same, and is controlled by the adjustable resistor R. It will be noticed that the cathode resistors R₁ and R₂ of Fig. 3 have been coalesced into a single variable resistance.

Suppose, now, that tube A is operated at potential such that it is relatively ineffective unless its bias is made less than the value which causes the amplifier tube to amplify reasonably well. Then, decreasing R from large values toward a certain minimum, there is obtained the following sequence of performance characteristics. First, R is so great that the amplifier tube does not amplify, nor does the tube A produce appreciable regeneration. This condition would occur when listening to very strong signals, when amplification is not needed, nor increased selectivity. Second, R is reduced until a considerable amount of amplification is obtained, but no appreciable amount of feed-back. Thirdly, R is reduced to a value where the feed-back becomes such as to reduce the total effective tuned circuit resistance to a value which gives a desired selectivity, and also, in virtue of what has been described in connection with Fig. 1, a desired maximum amplification. Thus, adjustment of R simultaneously alters both amplification and selectivity, making both approach an upper limit

which may be designed to be independent of frequency.

Stated another way when the resistor R is adjusted to have a large value the amount of regeneration is negligible, and the amplification is small, the fidelity being a maximum. Such an adjustment is suitable for receiving local stations where fidelity rather than selectivity is desired. When the resistance is made small, however, the regeneration becomes sufficient to make the circuit highly selective and the amplification increases because the amplifier tube mutual conductance increases, and, additionally, because the tuned circuit becomes more efficient. This arrangement can be used to a special advantage in portable receivers having only one or two stages of amplification because in such receivers an artificial increase in selectivity would be especially valuable.

In practice, an auxiliary tube accompanying each amplifier tube would increase the number of tubes in a receiver to an objectionable extent and, therefore, I contemplate the use of an amplifier tube which has an auxiliary plate, or an auxiliary control grid, for the purpose of effecting the regeneration. Accordingly, there is shown in Fig. 5 a vertical section of an electron discharge tube designed to combine both amplification and regeneration in a single tube. The reference numeral 7 designates the glass envelope of the tube, the numeral 8 designates the cathode of the tube, the numeral 9 represents the control grid of the tube, one of the anodes being designated by the numeral 10 and the other anode by the numeral 11. The smaller anode, or plate, 10 is the regenerating plate, and corresponds to the plate of tube A of Fig. 4. There is a screen 11' disposed around the main, or amplifying, plate 11, but a screen is not absolutely required around the regeneration plate, although for the sake of completeness such a screen 10' has been shown disposed around the plate 10.

The part of the grid 9 which controls the flow of electrons through the regeneration plate is made of wire 9' sufficiently large, or spacing sufficiently close, so as to preclude appreciable regenerative amplification until the control grid bias has been reduced to a point giving a predetermined amplification. This refinement is not absolutely necessary, as the feed-back couplings can be arranged so that the maximum desired regeneration is attained simultaneously with maximum mutual conductance as the control grid bias is decreased.

In what has preceded, it has been assumed that the pair of tubes, or composite amplifier-regeneration tube, acts on its input circuit regeneratively, and produces amplified voltage in its output circuit. This system is satisfactory for each tube has a tuned input circuit which it may regenerate, the detector regenerating its input, while the antenna and radio frequency tubes act as the sources of signals which are coupled to the thus regenerated circuits. However, in some circumstances it may be preferable to have each pair of tubes, or composite tube, act on the same circuit. Hence, there is shown in Fig. 6 an arrangement for securing such an operation, and it will be noted that Fig. 6 shows a modification of Fig. 4 wherein the amount of regeneration is uni-controlled along with the mutual conductance of the tube which feeds into the circuit regenerated.

In Fig. 6, then, the tuned input circuit of tube 2 is capacitively coupled by the condenser K to the anode circuit of the preceding amplifier tube 75

1. It will be observed that the arrangement shown in Fig. 6 is similar to the arrangement of Fig. 3, with the exception that the adjustable resistor R is connected in the grounded cathode 5 lead of tube 1 , the high potential side of the resistor R being connected by a lead $6'$ to the cathode of the tube A . The negative terminal of the potential source B' is grounded, and the manner of coupling the coil L , the coil T_1 and the coil T_2 10 is shown. The tube 1 is connected to the source of high frequency energy having a potential E_1 to be amplified, and the tube 1 may be the first radio frequency amplifier of a receiver, for example. As pointed out heretofore, in the modification 15 shown in Fig. 6 the amount of regeneration of the tuned circuit K , C , L is simultaneously controlled with the mutual conductance of the tube 1 which feeds into the tuned circuit which is being regenerated.

20 There is shown in Fig. 7 an arrangement embodying a composite tube combining the functions of the tubes 1 and A of Fig. 6. In this composite tube, as in the case of the tube shown in Fig. 5, there is disposed within the common envelope 7 , the cathode 8 , the small auxiliary regeneration anode 10 , and the larger amplifying anode 11 , both of the anodes being surrounded respectively by the screens $10'$ and $11'$. The amplifier control grid 9 is shown separate however from the regenerator control grid $9'$, and screen $9''$ is disposed between the control grids 9 and $9'$ and functions to prevent capacity coupling between control grid 9 and the tuned output circuit of the tube 7 . The grounded lead of the cathode 35 8 includes the adjustable resistor R , shunted by the high frequency by-pass condenser 12 , it being understood that the resistor R functions in the same manner as described in connection with Fig. 6.

40 The tube shown in Fig. 7 may be simplified, however, by employing a single anode 13 , as shown in Fig. 8. This may be done while maintaining uni-control of the amount of the regeneration and the variation of regeneration with 45 frequency, if the properly chosen compound coupling is employed, not to feed back the voltage to the tuned circuit, but to pick up the voltage from the tuned circuit to apply to the regeneration grid $9'$ through a lead 15 connected between the grid $9'$ and one side of the coil T_1 . It will be observed that this differs from the connection in Fig. 7 wherein the grid $9'$ is connected by a lead 14 to the high potential side of the coil L , while the regeneration anode 10 is connected by a lead 50 $14'$ to one side of the coupling coil T_1 . It will be noted that a screen $13'$ is disposed around the single anode 13 , and that the screen $9''$ is disposed between the grids 9 and $9'$.

55 In the arrangements described above, the network including coil T_1 , coil T_2 , and the shunt condenser K_2 has been used merely as illustrative of any desired method for obtaining an effective mutual impedance having suitable variation with frequency. It is possible, however, to obtain good 60 results with the compound coupling by arranging the geometry of the regeneration grid $9'$ of the tube shown in Fig. 8 so that no appreciable regeneration is introduced until the value of the resistor R is reduced to a point where the mutual 65 conductance of the amplifying part of the tube is nearly a maximum. In this way the single volume control R , if its resistance is reduced, first increases amplification in normal fashion, then increases selectivity with a resultant further increase in amplification.

Such an arrangement is shown in Fig. 9. In this figure the regeneration grid $9'$ is indicated as of a closer mesh than the amplifying grid 9 so that regeneration is small if R is large. Also, a metallic disk $8'$ of conducting metallic material 5 around the cathode opposite the shielding $9''$ between the grids is indicated, to prevent unnecessary screen current. The regeneration grid $9'$ is tapped onto the tuned circuit, by a lead 15 , at a point where, with R at the minimum safe value, 10 regeneration is as strong as desired at all frequencies, and with tubes as poor as considered fit for sale. With extra good tubes, and/or at some frequencies, oscillation will result from advancing the volume control too far. However, it is 15 believed that this is a desirable possibility, rather than otherwise, in cheap sets having few tubes. If the user does not like oscillations he does not need, of course, to produce them. A loop antenna, followed by two stages of amplification 20 such as shown in Fig. 9, and a pentode high power detector directly feeding into a loudspeaker should make an excellent portable set.

Such a portable light battery operated receiving arrangement is diagrammatically shown in 25 Fig. 10 wherein the tubes 20 , 21 , 22 are to be understood as being of the type shown in Fig. 5, the regeneration anode 23 of tube 20 being coupled, as at L , to the tunable input circuit of tube 20 . The input circuit is preferably a loop antenna comprising a coil 24 shunted by a fixed condenser K_1 in series with a variable tuning condenser 25 . The fixed condenser K_1 is shunted by the secondary of the coupling transformer L , and the regeneration anode lead $23'$ includes 30 the primary coil L_1 of the coupling transformer L in series with a coil 26 , inductively coupled to the coil 24 , and having one terminal thereof connected to the positive terminal of a source of anode potential B (not shown).

The amplifier anode of tube 20 is connected to 40 the positive terminal of a source of anode potential through the primary coil 27 , the latter being coupled to a secondary coil 28 shunted by a condenser coupling 29 which functions in a manner similar to the coupling condensers K of the various figures. The condenser 29 is shunted by the variable tuning condenser 30 , a coil 31 being connected between the high potential sides of the condensers 29 and 30 . The cathodes of tubes 20 and 21 are connected to ground through 45 a radio frequency by-pass condenser 32 , and the rotors of the tuning condensers 25 , 30 , as well as the rotor of the detector tuning condenser 40 , are grounded so that they may be simultaneously adjusted by a common mechanical uni-control 50 mechanism 41 .

The regeneration anode $21'$ of tube 21 is tapped onto a point on coil 27 through a lead 33 which includes the coil 34 coupled to the coil 31 . The common cathode lead of tubes 20 and 21 , also, is 60 connected to ground through a path including the resistor R_2 in series with the adjustable resistor R employed for varying the mutual conductance of tubes 20 and 21 , as well as the variation of regeneration of these two tubes. The 65 coupling network between the amplifier anode circuit of tube 21 and the input electrodes of detector tube 22 is similar to the coupling network arrangement shown between tubes 20 and 21 , and therefore need not be described in detail. 70 The grid biasing network 50 in the grounded lead of the cathode of tube 22 provides biased grid detection, although it is to be clearly understood that the detector may be operated with a leaky grid condenser instead. 75

The reference numeral 51 is to be understood as representing any desired type of reproducer adapted to be disposed in the amplifier anode circuit of detector tube 22. Of course, as is well known in the art, a common source of potential B may be provided for the various circuits of tubes 20, 21 and 22. Furthermore, there may be employed in the tube 22 a so-called suppressor grid; that is a grid connected to the cathode within the tube may be disposed between the shield for the two anodes and the two anodes themselves, such a pentode tube suppressor grid being well known in the art.

The receiver shown in Fig. 10 operates in the following manner. Regeneration anode 23 is coupled to the resonant input circuit by a simple untuned inductance between loop 24 and coil 26, and by a capacity coupling K_1 connected into the anode circuit by way of transformer L'L. This transformer allows segregation of steady potentials while allowing the coupling as a whole to be equivalent to the simple mutual capacity coupling shown in Fig. 1 provided the natural frequency of circuit $K_1 L$ is low compared to signal frequency. This compound coupling between regeneration anode 23 and the input circuit is arranged to keep the effective resistance of the input circuit low and independent of frequency when R is kept =0.

The relay anode of tube 20 is capacitively coupled to the tuned input circuit of tube 21 by the transformer 27—28 in combination with coupling condenser 29 as explained above. The regeneration anode 21' of tube 21 is however compound coupled to the resonant input circuit of tube 21, the magnetic coupling being the mutual inductance between coils 34 and 31 while the capacity coupling means is a portion of that coil 27 which couples the main anode of tube 20 to the resonant input circuit of tube 21. The main anode of tube 21 is coupled to the resonant input circuit of detector 22, and this resonant circuit is regenerated, in exactly similar fashion. Resistance R controls both the amplification and regeneration of the first two tubes as described in connection with other figures.

In the arrangements described up to this point, regeneration has been assumed to be obtained by a separate tube, or a separate electrode in a screen grid tube. However, if a screen grid tube is used, the feed-back coil may be put in its plate, or screen circuit. Thus, in Fig. 11 the screen grid tube 60 has its anode circuit capacitively coupled to the tunable input circuit of tube 61, the input electrodes of tube 61 being connected across the tuning condenser 62. This coupling network has been shown in Fig. 2, and need not be described in any further detail. It should be noted that the anode of tube 60 is regeneratively coupled to the tunable input circuit coil 63 by means of a coil 64.

The reason why the arrangement of Fig. 11 is a possibility with screen grid tubes is that radio frequency potentials on the plate of tube 60 are prevented from appreciably affecting the grid thereof through the plate-grid capacity, and the load impedance is so small relative to the plate impedance that no appreciable reduction in the current through tickler coil 64 is caused by tuning the load circuit. It is preferable to locate the tickler coil in Fig. 11 at the low potential end of the grid coil to minimize capacity coupling.

Fig. 12 shows a modification wherein the coil 64 is disposed in the screen grid circuit of the tube

60. The arrangement of Fig. 12 is possible because as there is very little load in the circuit of tickler coil 64, very little radio frequency potential is built up on the screen. Hence, maximum feed-back occurs at exact resonance tuning of 5 the input, and the screen potential being nearly constant allows the screen to carry out its normal function of screening around the plate.

While I have indicated and described several systems for carrying my invention into effect, it 10 will be apparent to one skilled in the art that my invention is by no means limited to the particular organizations shown and described, but that many modifications may be made without departing from the scope of my invention as set 15 forth in the appended claims.

What I claim is:

1. In combination, an amplifier tube provided with an output circuit, a succeeding resonant circuit adapted to be tuned throughout a predetermined frequency range, means for coupling the output circuit of said tube to said resonant circuit comprising a fixed condenser common to said two circuits, and means independent of the coupling means for controlling the total effective 25 resistance of said resonant circuit.

2. In combination, an amplifier tube provided with an output circuit, a succeeding resonant circuit adapted to be tuned throughout a predetermined frequency range, means for coupling 30 the output circuit of said tube to said circuit comprising a fixed condenser common to said two circuits, and means independent of the coupling means for controlling the total effective resistance of said resonant circuit to a value which is 35 sufficiently low for good amplification and sufficiently constant to maintain both amplification and selectivity satisfactorily constant.

3. In combination, an amplifier tube provided with an output circuit, a succeeding resonant 40 circuit adapted to be tuned throughout a predetermined frequency range, means for coupling the output circuit of said tube to said circuit comprising a fixed condenser common to said two circuits, means independent of the coupling 45 means for controlling the total effective resistance of said resonant circuit, and a single operating means for uni-controlledly adjusting the amplifying power of said tube and the total effective resistance of said resonant circuit. 50

4. In combination, an amplifier tube provided with an output circuit, a succeeding resonant circuit adapted to be tuned throughout a predetermined frequency range, means for coupling the output circuit of said tube to said circuit comprising a fixed condenser common to said two circuits, and means independent of the coupling means including an electrode connected to a feedback circuit coupled to the resonant circuit for controlling the total effective resistance of 60 said resonant circuit, said electrode being disposed within said amplifier tube. 55

5. A radio receiver comprising at least two cascade radio frequency amplifier stages and a power detector stage, each of said stages comprising input and output circuits and a tube which has in addition to the usual cathode, control grid and anode, an auxiliary anode regeneratively coupled to the input circuit of its respective stage, and a common fixed condenser for coupling 70 the input circuits of the stages to the respective output circuits of the preceding stages, and a common means for controlling the amplifying power of the two amplifier stages as well as the regeneration of at least one of the stages. 75

6. In combination a circuit including a tube having an input circuit and a plate circuit, a condenser tuned resonant circuit, means including a mutual impedance for coupling the plate circuit to said tuned resonant circuit, said mutual impedance being substantially proportional to wave length over the tuning range, and means for automatically adding negative resistance to said tuned circuit in amount which increases with increasing frequency, while maintaining said resonant circuit substantially uncoupled from said input circuit except by the repeater action of the tube.

7. An interstage coupling arrangement for obtaining uniform amplification and selectivity of signals transferred between a pair of cascaded vacuum tube stages comprising a tunable circuit including a variable condenser, an inductance and a fixed condenser connected to form a closed circuit, the output electrode of the first stage being coupled to the fixed condenser, the input electrode of the second stage being energized from said tunable circuit, and means coupled to said inductance for controlling the effective resistance of said tunable circuit.

8. An interstage coupling arrangement for obtaining uniform amplification and selectivity of signals transferred between a pair of cascaded vacuum tube stages comprising a tunable circuit including a variable condenser, an inductance and a fixed condenser connected to form a closed circuit, the output electrode of the first stage being coupled to the fixed condenser, the input electrode of the second stage being energized from said tunable circuit, and means for controlling the effective resistance of said tunable circuit comprising an auxiliary tube having its input electrode connected to the resonant circuit and

its output circuit regeneratively coupled to the resonant circuit.

9. An interstage coupling arrangement for obtaining uniform amplification and selectivity of signals transferred between a pair of cascaded vacuum tube stages comprising a tunable circuit including a variable condenser, an inductance and a fixed condenser connected to form a closed circuit, the output electrode of the first stage being coupled to the fixed condenser, the input electrode of the second stage being energized from said tunable circuit, and means for controlling the effective resistance of said tunable circuit comprising an auxiliary tube having its input electrode connected to the resonant circuit and its output circuit regeneratively coupled to the resonant circuit, and simultaneously variable cathode resistors for said auxiliary tube and the tube of the first stage.

10. An interstage coupling arrangement for obtaining uniform amplification and selectivity of signals transferred between a first vacuum tube provided with at least an output electrode and an auxiliary electrode and a second vacuum tube provided with at least an input electrode, comprising a tunable circuit including a variable condenser, an inductance and a fixed condenser connected to form a closed circuit, the output electrode of the first tube being coupled to the fixed condenser, the input electrode of the second tube being energized from said tunable circuit, and means for controlling the effective resistance of said tunable circuit comprising the auxiliary electrode contained in the tube of the first stage and a feedback circuit connected thereto inductively coupled to the tunable circuit.

WALTER VAN B. ROBERTS.
